(21) Appl. No.: **29/135,255**

The ornamental design for a retractable cover for tool box
mounted in a truck bed, as shown and described.

(22) Filed: **Jan. 9, 2001**

DESCRIPTION

(51) LOC (7) Cl. **12-16**

FIG. 1 is a top plan view of a retractable cover for tool box
mounted in a truck bed, in a closed position and assembled
for transportation, showing my design;

(52) U.S. Cl. **D12/401**

FIG. 2 is a cross-sectional view taken along lines 2—2 of
FIG. 1, thereof;

(58) Field of Search D12/401, 406,
D12/412, 414.1, 415, 423; 296/98-100,
100.1-101; 160/26, 33, 32, 36, 133

FIG. 3 is a right side elevation view thereof;

(56) **References Cited**

FIG. 4 is a front elevation view thereof;

U.S. PATENT DOCUMENTS

FIG. 5 is a rear elevation view thereof;
